DESIGN FOR A SPECTACLE FRAME OR SIMILAR ARTICLE

Nadja Buckley, New York, N. Y.

Application September 4, 1947, Serial No. 141,197

Term of patent 7 years

(Cl. D57—1)

To all whom it may concern:

Be it known that I, Nadja Buckley, a citizen of the United States of America, residing in the city, county, and State of New York, have invented a new, original, and ornamental Design for a Spectacle Frame or Similar Article, of which the following is a specification, reference being had to the accompanying drawing, forming a part thereof.

In the drawing:

Fig. 1 is a front perspective view of a spectacle frame, showing my new design;

Fig. 2 is a side elevational view thereof; and

Fig. 3 is a fragmentary top plan view of the frame.

The essential features of my design reside in the configuration of the temples shown in full lines.

I claim:

The ornamental design for a spectacle frame or similar article, substantially as shown and described.

NADJA BUCKLEY.
